UNITED STATES PATENT OFFICE

FELIX FREDERIC RUAU, OF DEPTFORD, LONDON, ENGLAND

CIGARETTE MAKING MACHINE

Application filed July 1, 1929, Serial No. 375,232, and in Great Britain July 9, 1928.

This invention is for improvements in or relating to cigarette making machines, and relates more particularly to an apparatus for applying cork or like tips to a travelling web of cigarette paper.

In such machines, cork or like tipped cigarettes are manufactured by applying at regular intervals along a travelling web of cigarette paper, strips of cork or like material which are equal in width to the web of cigarette paper, and in length to twice the length of the tip of a cigarette so that when the web of cigarette paper and the tobacco are formed into a continuous rod, cork bands are formed around the rod at intervals spaced apart by a distance equal to twice the length of a cigarette. The rod thus formed is severed at the mid-length of each of the said bands thereby producing cork tipped cigarettes wherein the mouth-piece of each cigarette is disposed adjacent to that of its neighbour.

In machines of the above character the cork tips are secured to the paper by gum which is applied to the web of cigarette paper by feeding the same between a gumming roller and a pressure roller. As it occasionally happens that a cigarette making machine is stopped when that portion of the gumming roller which applies the gum to the web of cigarette paper is in contact with the paper, it is found that on re-starting that the paper becomes firmly attached to the gum roller.

Further, it is found in practice that the gum on the gum applying portion of the gumming roller becomes partly dried, and very sticky when the machine has been stopped for a short time, and upon re-starting, the web of cigarette paper is liable to become secured to the gum applying portion of the roller and consequently the web breaks and the machine has to be stopped to repair the damage.

The present invention consists of an apparatus for applying cork or like tips to a travelling web of cigarette paper which comprises a pressure roller arranged to press a web of cigarette paper into engagement with a gumming roller, and means opera-

tively connected to the pressure roller operable to move the said roller out of proximity to the gumming roller when the cigarette making machine is stopped.

The invention will be more particularly described with reference to the accompanying drawing which shows a tipping apparatus of the kind described in specification No. 251,322 with the invention applied thereto.

Referring to the drawing, the tipping apparatus comprises an engraved gum applying roller 1 which is supplied with gum by a furnishing roller 2 arranged to rotate in a gum bath 3.

A reciprocating doctor 4 is arranged so as to scrape the surplus gum from the plain portion of the gumming roller.

A pressure roller 5 is mounted so as to press the web of cigarette paper into contact with the surface of the gumming roller 70 when the engraved portion of the said roller is in proximity to the paper. The pressure roller 5 is operated by a cam 6 mounted on one end face of the gumming roller and is operable to raise periodically the cam roller 75 7 mounted on the bell crank lever 8. The bell crank lever 8 is secured to the spindle 9 on which the arm 10 carrying the pressure roller 5 is mounted.

A spring 11 is arranged to force the roller 80 5 into proximity with the gumming roller 1 against the action of the cam 6.

One end of a link 12 is secured to the free end of an arm 12^a arranged to extend radially from the spindle 9, the other end of which is secured to one arm of a bell crank lever 13, the other arm of which is controlled by a rod 14 which is operable to slide in the main frame 15. The rod 14 is arranged to be operated by a pivoted lever 16 connected 90 by a link 17 to a crank 18 fixed to the shaft 19 of the striking gear.

In the drawing the apparatus is shown in the position the same occupies when the machine is stopped. When the striking gear shaft 19 is rotated in the direction of the arrow the lever 16 will be moved out of engagement with the end of the rod 14 which is permitted to move axially.

The bell crank lever 13 is arranged to be 100

retained in the position shown in the drawing by a pawl 20 each time the machine is stopped unless the pawl is held in the inoperative position, as hereinafter described.

The pawl 20 is formed on one end of a bell crank lever; the other end of the said lever being furnished with a roller 21 arranged to engage with a cam 22 which is driven in synchronism with the gumming roller 1.

The operation of the apparatus is as follows:—

When the cigarette making machine is in operation the rod 14 is free to move axially and the bell crank 13 is free to oscillate about the pivot thereof as the pressure roller 5 is raised and lowered by the action of the cam 6 and spring 11.

The web of cigarette paper 23 is therefore periodically pressed into contact with the gumming roller every time the gum applying portion of the said roller is in proximity to the paper.

As the shaft of the striking gear is rotated to stop the machine the rod 14 is moved to the left by the lever 16 and bears upon the free end of the bell crank 13 and so raises the pressure roller 5 out of proximity with the gumming roller 1. Further, the free end of the bell crank lever 13 passes under the nose of the pawl 20 which serves to retain the lever 13 in the position shown in the drawing until the pawl 20 is lifted clear of the bell crank lever 13 by the rotation of the cam 22. The crank 13 and pawl 20 are interconnected by a spring 24. When the cigarette making machine is re-started the pawl 20 serves to retain the parts in the position shown in the drawing until the cam 22 oscillates the pawl 20 and releases the lever 13 from engagement therewith. The raised portion of the cam 22 is so arranged with respect to the gum applying portion on the gumming roller 1 that the pressure roller 5 is prevented from pressing the web of cigarette paper into contact with the gumming roller until the gum applying portion has passed into contact with the furnishing roller 2 and received a fresh supply of gum. The raised portion of the cam 22 is set so that when the roller 21 is in engagement therewith and the pawl 20 is maintained in an inoperative position, the gum applying portion of the gumming roller is in contact with the furnishing roller and is therefore supplied with fluid gum.

After the web of cigarette paper has received gum from the gumming roller 1 the same is led around the guide roller 24 and receives a tip severed by a rotary cutter 26 from a web of cork 25. The tipped web of cigarette paper passes beneath pressure rollers 27 and 28 and is led away to the filling channel of the cigarette making machine.

Thus it will be seen that according to the

present invention there is provided means which will ensure that the pressure roller is lifted out of contact with the paper when the machine is stopped, and the paper is prevented from contacting with the engraved roller until the latter has received a supply of fluid gum upon the gum applying portion thereof.

What I claim as my invention and desire to secure by Letters Patent is:—

1. An apparatus for applying cork or like tips to a travelling web of cigarette paper which comprises a pressure roller arranged to press a web of cigarette paper into engagement with a gumming roller, means operatively connected to the striking gear of the cigarette making machine arranged to maintain the pressure roller in proximity to the gumming roller whilst the machine is in operation and automatically move the pressure roller out of engagement when the striking gear is operated to stop the said machine.

2. An apparatus for applying cork or like tips to a travelling web of cigarette paper which comprises a pressure roller arranged to press a web of cigarette paper into engagement with a gumming roller, means operatively connected to the driving mechanism of the cigarette making machine arranged to maintain the pressure roller in engagement with the applying portion of said roller whilst the machine is in operation and remove the same out of proximity therewith when the machine is stopped, and locking mechanism arranged to hold the pressure roller out of proximity to the gumming roller for a predetermined period after the cigarette machine has recommenced the operation thereof.

3. An apparatus for applying cork or like tips to a travelling web of cigarette paper which comprises a pressure roller arranged to press a travelling web of cigarette paper into engagement with a gumming roller, link mechanism operatively connected to the striking gear of the cigarette making machine operable by the movement of said gear to hold the pressure roller in proximity to the gum applying portion of the said roller while the cigarette machine is in operation and move the same out of proximity therewith when the machine is stopped and cam operated locking mechanism arranged to lock the said link mechanism when the machine has been stopped and maintain the same in the locked position for a predetermined period after the cigarette making machine has been re-started.

4. In an apparatus for applying cork or like tips to a travelling web of cigarette paper, the combination with means for applying gum to said web, of mechanism operable to periodically press the web into engagement with said gum applying means, control

means for suspending the operation of said mechanism, and means operatively connected with said control means for retaining said mechanism out of web pressing position when the operation of said mechanism is suspended.

5. In apparatus for applying cork or like tips to a travelling web of cigarette paper, the combination with means for applying 10 gum to said web, of mechanism operable to periodically press the web into engagement with said gum applying means, control means for suspending the operation of said mechanism, and means operatively connected 15 with said control means for moving said mechanism out of web pressing position when operation thereof is suspended.

6. In apparatus for applying cork or like tips to a travelling web of cigarette paper, 20 the combination with means for applying gum to said web, of mechanism operable to periodically press the web into engagement with said gum applying means, control means for suspending the operation of said 25 mechanism, means operatively connected with said control means for moving said mechanism out of web pressing position when operation thereof is suspended, and means for retaining said mechanism in such 30 position for a predetermined period upon subsequent initiation of operation of the apparatus.

In witness whereof I have hereunto set my hand.

25 FELIX FREDERIC RUAU.
